SAFETY SIGNAL SWITCH FOR
AUTOMOBILES

Leo J. Kobiella, Sebastopol, Calif.

Application February 25, 1939, Serial No. 258,553

2 Claims. (Cl. 200—59)

This invention relates to a driving signal system for an automobile, and a general object of this invention is to provide a practical and efficient device to supersede the hand and arm method of signaling.

Another general object of this invention is to recommend in a device of this character, a system of colored light signals that are dependable both day and night, and to provide a controlling means therefor that is foolproof and convenient to operate.

Another general object is to obtain in an arrangement of the character indicated, a construction which permits of mass production in manufacture; facilitates quick assembly of the parts, and is easily installed, at a relatively small cost per unit, on all makes and types of motor cars.

More specifically the principal objects of this invention are, first, to provide a left turn indicating switch and a right turn indicating switch which may be operated to closed positions without removing the hands from the steering wheel; second, to provide in the steering wheel hub, a means for automatically returning said switches to open positions without any conscious effort of the operator; third, to recommend a stop signal switch in automatic operative arrangement with the accelerator pedal so that its operation requires absolutely no attention; fourth, to recommend an individual left turn indicating signal lamp and an individual right turn indicating signal lamp for the front, and an individual combination left turn and tail signal lamp and an individual combination right turn and stop signal lamp for the rear of the automobile; fifth, to recommend each of said turn signal lamps be provided with a conventional "flash" type electrical bulb and the tail and the stop signal compartments thereof with ordinary bulbs; sixth, to recommend for the steering wheel hub cover, a red and a green signal indicator lights to correspond with the colors of the left and the right turn signal lamp lenses respectively; and seventh, to recommend the wiring be arranged so that all of the circuits, switches and signal elements of this system derive their electrical current through the ignition switch of the automobile when said ignition switch is in the "on" position.

Other important objects and advantages of this invention will be apparent from a reading of the following description taken in connection with the drawings, wherein for purposes of il-

lustration I have shown a preferred embodiment of my invention. In the drawings:

Figure 1 is a horizontal top plan view of a steering wheel hub cover modified in accordance with this invention.

Figure 2 is a transverse vertical sectional view taken through Figure 1 approximately on the line 2—2 and looking toward the right in the direction indicated by the arrows.

Figure 3 is a horizontal view of the stationary 10 mounting member with hub cover removed, taken through Figure 4 approximately on the line 3—3 and looking downwardly in the direction indicated by the arrows.

Figure 4 is a transverse vertical sectional view 15 taken through Figure 1 approximately on the line 5—5 and looking inwardly in the direction indicated by the arrows.

Figure 5 is a horizontal sectional view taken 20 through Figure 4 approximately on the line 4—4 and looking downwardly in the direction indicated by the arrows.

Figure 6 is an enlarged vertical sectional view 25 taken through Figure 4 alongside of one of the steering wheel switches and showing the relation of the switch plunger to the plunger camming means for returning the plunger to an upward position after manual depression so as to automatically restore the switch to "off" position, the plunger being shown in "off" or normal 30 position wherein the steering wheel is in the normal straight ahead position as indicated by the arrows.

Figure 7 is an enlarged view similar to Figure 6 35 but showing the switch plunger depressed where- by the switch is in the "on" position, and showing the plunger depressed to a position to engage the camming spring, the latter having just disengaged the cam from the cam seat as the steering wheel was turned in the direction indicated 40 by the horizontal arrow, thereby allowing the cam seater spring to freely slide the cam under the camming spring to the opposite side thereof without opening the switch.

Figure 8 is an enlarged view similar to Figures 45 6 and 7 but showing the action of the parts as the steering wheel is returned toward the normal straight ahead position after being turned beyond the point shown in Figure 7, the cam seater spring having fully reseated the cam at 50 the opposite side of the camming spring, and the cam acting to thrust the camming spring upwardly, thereby elevating the plunger and thus automatically reopening the switch.

Figure 9 is an enlarged fragmentary sectional 55

elevational view taken through one of the individual switches such as is shown in Figures 4, 6, 7 and 8.

Figures 10 to 19 inclusive are views of the parts comprising each of the individual turn-signal switches:

Figure 10 is a vertical elevational view of the knurled clamping nut;

Figure 11 is a vertical elevational view of the shank, whereon the dotted lines indicate the outlines of the inner bore;

Figure 12 is a vertical elevational view of the casing;

Figure 13 is a longitudinal perspective view of the plunger;

Figure 14 is a horizontal perspective view of the upper dielectric washer;

Figure 15 is a horizontal perspective view of the conductive annulus;

Figure 16 is a horizontal perspective view of the lower dielectric washer;

Figure 17 is a perspective view of the expanding spring;

Figure 18 is a perspective view of one of the circuit closing balls;

Figure 19 is a perspective view of the other circuit closing ball.

Referring in detail to the drawings, and particularly to Figures 2 and 4, the numeral 5 generally designates the steering column of the automobile which includes the outside tube 6, the rotatable tubular steering shaft 7 and the inner stationary tube 8 which is arranged to inclose the conduit 9 in which the various conductors 10 are incased.

The numeral 11 generally designates the steering wheel which may be of any conventional design and possesses the well 12 in its hub which includes the upper relatively shallow part 13 and the central relatively deep part 14, the latter including the centralized flange 15 which immediately surrounds the taper bushing 16 which is rigidly fixed to the steering wheel hub and whereby the steering wheel is securely mounted relative to the steering shaft 7 and the steering column 5 by the nut 17 in a conventional manner, no invention being predicated on this manner of mounting.

The upper part 18 of the inner stationary tube 8 projects above the nut 17 into the center of the well 14 and telescoped on this upper end 18 is the split sleeve portion of the mounting member 19 which includes clamping ears 20 and 21 which are adapted to be drawn together by the bolt 22 which traverses them to clamp the said mounting member rigidly in place on the upper part 18 of the stationary tube 8, as is clearly shown in Figures 2, 4 and 5 of the drawings.

The upper portion of the mounting member 19 is formed into the substantially circular plate 23 which is positioned at a level above the top of the steering wheel hub and has in diametrically opposite sides thereof segmental apertures 24 and 24' as are clearly shown in Figure 3 of the drawings, said apertures being provided to facilitate quick assembly of the parts during installation.

Other openings 25 and 25', of circular form, are made in the plate 23, these openings being provided with insulating grommets 26 and 26' respectively, serve two purposes, first, they facilitate quick assembly of the camming springs and second, they provide inlets for the wires of the left and the right turn signal circuits respectively, as clearly shown in Figures 2, 3 and 4 of the

drawings. Another pair of circular openings are provided for mounting the left and the right turn indicating switches in diametrically opposed horizontal alignment with the openings 25 and 25'. A fourth pair of openings 27 and 27', of substantially circular form, are aligned and disposed adjacent the vertical edges of the segmental apertures 24 and 24', as clearly shown in Figure 3, and in Figures 2 and 3 it will be observed that in each of these openings is frictionally pressed a substantially U-shaped spring support 28 and 28' on the legs of which are overhanging feet 29 which overlie and rest upon the top of the plate at the opposite ends of the openings, and fixed on the bight portion of these supports 28 and 28' are miniature bayonet type bulb sockets 30 and 30' in each of which is mounted a circuit indicator bulb 31 and 31'. Binding posts 32 and 32' project below the bight portion of the socket supports 28 and 28' and are adapted for "snap-on" connections of the appropriate wires thereto as shown in Figure 2. The bulbs 31 and 31' project above the top of the plate 23 and are respectively received in tubular portions 33 and 33' which are adapted to fit snugly into 25 accommodating circular openings overlying the bulbs, the said openings being formed in the depressions 41 and 41' in the top of the dome 33 which overlies and rests upon the plate 23, as is clearly shown in Figures 1 and 2 of the drawings. Retainers 34 and 34' formed on the upper part of the tubular portions 33 and 33' rest upon the floor of the depressions and retain appropriately colored circuit indicator lenses 35 and 35', the color of the lens 35 being green and the color 35 of the lens 35' being red so as to appropriately correspond with the colors of the right and the left turn signal lamp lenses respectively, the colors of the indicator lenses being distinct in order to convey accurate information by the illumination thereof by the corresponding indicator bulb, of the establishing and maintenance of the appropriate turn signal circuit. The tubular portions are removable to facilitate indicator bulb replacement.

The steering wheel hub cover 33 is substantially concave-convex in form and has at its center a well or depression 36 in which is mounted an ordinary horn button switch mechanism, and the top surface of the horn button 37 is shaped to conform in flush contour with the convex curvature of the dome 33. In horizontal alignment with the horn button 37 the depressions 38 and 38' are arranged diametrically opposite each other the floors of which are at an approximate level with the top of the cable retainer grommet 39 and serve to retain the individual right and left turn signal switches 40 and 40' respectively, thus, it will be observed, that a recessed switch mounting seat is provided wherein the switch push-buttons are safely guarded against inadvertent operation by the drivers arm as it may pass over the hub cover in reaching for a fresh grip on the steering wheel when negotiating a turn. In addition to the depressions 38 and 38' 55 and in diametrically opposed vertical alignment with the horn button are depressions 41 and 41' within which are disposed the circuit indicator lenses 35 and 35' as shown in Figures 1 and 2, the depressions 38 and 38' being shown in Figures 70 and 4.

The hub cover dome 33 terminates at its periphery in a depending flange 42 overlapping an annular flange 43 which projects above that part of the steering wheel hub which immediately 75

surrounds the upper end of the shallow portion of the well 12, said two flanges cooperating to form a safe and relatively close hub well closure.

The hub cover dome may be formed of a suitable plastic material, preferably some synthetic composition such as Tenite, Bakelite, Catalin, Plascon, etc., which may be molded into the required shape, polished and colored to harmonize with the instrument panel of the automobile.

10 The hub cover dome is secured in place on the plate 23 by mounting the individual turn switches 40 and 40' on the dome and against the plate as shown in Figure 4, thereby obviating the necessity of unsightly screw or bolt heads.

15 The stationary mounting member 19 which rigidly supports the dome 23 may be formed of some light weight metal that may be die cast into the required shape, and it should be observed in Figure 5 that a vertical key 56 is formed on the interior of the split sleeve portion of this member and telescoped into an accommodating key-way provided in the upper end of the stationary tube 8, said key and key-way interlocking to form a rigid, stabilized steering 20 wheel unit. It should also be observed that six keys 58' (three of which are visible on Figure 4) are formed as integral catches on the under side of the plate 23, said keys or catches being spaced and adapted to fit into three accommodating key-ways 58 which are incidentally formed in each switch during the assembly thereof, said keys and key-ways interlocking to stabilize the switches during installation and thereafter.

Now referring to the steering wheel 11 in Figures 2 and 4 it will be observed that the shallow portion 12 of the hub well terminates into an annular ledge or shoulder 13 the floor of which is formed into a circular groove or slot 44 which is under-cut at its opposite sides as indicated by the numerals 45 and 45' and comprises the over-hanging flanges 61 and 61'.

In diametrically opposed generally horizontal alignment of the slot 44 as shown in Figure 5, are ramps or wedges 46 and 47 which will hereinafter be referred to as "cam-seats," the side edges of which project into the groove extensions 45 and 45' formed by the overhanging flanges 61 and 61', which cam-seats are equipped with flat headed set screws 48 and 48' which are adapted to be turned down to lock the cam-seats in adjusted positions in any desired location within the slot. The principal advantage of "adjustable" type cam-seats lies in the flexibility attained thereby, however, flexibility is not essential to the efficiency of operation of the parts involved, therefore, as an alternative to the adjustable cam-seats just described, rigid cam-seats may be employed, and these may be achieved by limiting the slot 44 to a semi-circular arc terminating in abrupt slopes, said slopes serving the purpose for which the present cam-seats are intended, however, the slopes or ramps corresponding to the cam-seats 46 and 47, must slope in a forward direction when the steering wheel is in a normal straight ahead position as shown in Figures 5 and 6 of the drawings.

In operative relationship with the cam-seats 46 and 47 are companion cams 49 and 50 which are normally seated on the inclined plane of their related cam-seats, these cams having rounded ends and formed with wedge shaped wings 51 projecting from their opposite sides and extend under the overhanging flanges 61 and 61' and are thereby slidably confined within the slot 44. These wings 51 are tapered toward the foot

end of the cam-seats 46 and 47 so that the cams normally assume a raised inclined position as shown in Figures 6 and 8.

A spring 52 (which will hereinafter be referred to as the "cam-seater-spring") is composed of 5 a series of V-shaped contours reversed with respect to each other and having their apices loosely confined under the overhanging flanges 61 and 61', said spring being disposed within the slot 44 between the cams 49 and 50 and on the 10 sides thereof remote from the cam-seats 46 and 47, as is clearly shown in Figure 5 of the drawings, whereby the cams 49 and 50 are constantly urged to assume the positions shown in Figures 15 6 and 8.

The numeral 51 on Figure 5 of the drawings designates a portion of the outer overhanging flange 61 removed to facilitate admittance of all of the camming parts into the slot 44 and through which all of the assembly may be removed.

Diametrically opposed pairs of ears 54 and 54', secure by bolts designated 55 and 55', to the lower sleeve portion of the casting 19, a right and a left horizontal spring members 58 and 25 58', (hereinafter referred to as "camming-springs") said camming-springs having lateral turned up sides 60 and 60' on the free ends thereof, these portions normally positioned astride the top surface of the overhanging flanges 61 and 61' over the slot 44.

The purpose of the camming-springs is to eliminate any possible dead-spot from the steering wheel camming assembly. If these members are omitted a dead-spot results wherein the 35 switches are rendered inoperative whenever the cams may be in a position directly beneath the switch plunger. The camming-springs 58 and 58' eliminate the possibility of dead-spots and the lateral turned up sides 60 and 60' serve to 40 dislodge the cams from their related cam-seats simultaneously urging them downwardly, against the tension of the cam-seater-spring, until the said cams are fully unseated and at a horizontal level flush with the top surface of the overhanging flanges where they are temporarily positioned immediately in front of their related cam-seats, as shown in Figure 7. In this disengaged position the cams 49 and 50 are yieldably urged by the cam-seater-spring 52 to pursue 45 their related cam-seats 46 and 47 as the steering wheel is turned, said pursuance being effected with the cam in a flat unseated position wherein it is free to pass under and to the opposite side of the respective camming-springs 58' and 58 55 without effecting elevation thereof. The lateral turned up sides 61 and 61' also prevent any sticking or scraping when the steering wheel is turned or when the cams are to be operatively engaged with the plungers of the individual turn 60 indicating switches.

The camming-springs 58 and 58' are stationarily located directly under the plungers 82 of the respective ones of the turn indicating switches 40 and 40', as clearly shown in Figures 4, 6, 7 65 and 8, and the said plungers do not come into direct contact with the cams at any time, thus it is evident that as the related one of the camming-springs is elevated by engagement therewith of the corresponding cam, the elevation of the camming-spring effects elevation of the corresponding switch plungers.

As heretofore indicated, Figures 6, 7 and 8 of the drawings show progressive stages in the co-operation between the cam and cam-seat with 75

respect to the camming-spring and the plunger of the individual turn indicating switch, and from these figures it will be obvious, considering that Figure 6 shows the neutral or normal straight ahead position of the steering wheel, that as the indicated turn is executed, the cam and the cam-seat corresponding to the depressed switch plunger are automatically disengaged so that they are free to pass under the camming-spring to the opposite side thereof without elevating the spring to cause elevation of the plunger, since the cam lies flat in this arrangement of the parts, as shown in Figure 7.

However, as the direction of action is reversed in returning the steering wheel from the turned position toward the straight ahead position, sufficient pressure having previously been exerted by the expansion of the cam-seater-spring 52 to push the corresponding cam toward and up along the ramp of its cam-seat so that the cam again assumes its normal, inclined, elevated position, on the opposite side of the camming-spring, it is evident, that, with the cam in this elevated position, the reverse movement of the body containing the cam, relative to the corresponding stationary switch and its camming-spring, will sufficiently elevate the camming-spring and consequently the switch plunger to automatically reset the switch to "off" position.

30. The displacement and replacement of the cams from and back to its related cam-seat as illustrated in Figures 6, 7, and 8, occurs every time the steering wheel is turned sufficiently to permit it, regardless if the switch plunger is depressed or not, however, the wear to the parts involved is negligible.

Referring now to Figures from 9 to 19 inclusive, which are representative of each of the individual turn indicating switches 48 and 48' and of the various parts comprising each of said switches, the numeral 62 designates the generally cylindrical solid plunger which is vertically slidable in the bushing or neck 63 which is exteriorly threaded as indicated by numeral 64, this threaded portion projects through vertically aligned openings in the plate 23 and the dome 53, a shoulder formed by the shank portion 65 of the neck 63 abuts against the under side of the plate and is provided with three equi-spaced notches 59 for crimping the switch case to the shank in a compact assembled unit, said crimped indentations 59 interlocking with three companion catches or keys 59' which serve to stabilize the switch during installation thereof and thereafter, complementing the clamping nut 66.

Within the bore of the shank portion 65 is an angular outset 67 terminating in an annular edge 68 which comprises an inclined detent groove into which the conductive balls 69 and 70 are arranged to project to positively retain the switch plunger 62 in "off" position until subsequent manual depression thereof. The arrangement provided to exert constant outward pressure against the conductive balls 69 and 70, is comprised of the coil, expanding spring 71 loosely confined in the transverse passage 72 which is formed in the plunger 62.

Surrounding and crimped to the shank 65, is a cylindrical casing 73 which has a rectangular side opening 74 through which projects the connector arm 75 which is adapted for the binding post 76, this arm projects from the conductive annulus 77 which is concentrically arranged in the casing 73 and insulated therefrom by being inlaid in

the dielectric washer 78 and held securely in its place by the dielectric washer 78.

It will be observed that the orifice in the dielectric washer 78 is larger than that of the shank 65, above it, or of that of the conductive annulus 77, below it, thus is provided a detent groove flanked above and below by electrical conductors, thus, when the plunger 62 is in the position shown in Figure 9, the switch is in the "on" position, because the conductive balls 69 and 70 are pressed into contact with both the conductive annulus 77 and the conductive shank rim 65, thus bridging the detent groove provided by the dielectric washer 78 and thereby closing the electrical circuit by grounding the conductive annulus 77 through the conductive shank 65 to the conductive plate 23 against which the shank abuts.

When the plunger 62 is in the position shown in Figure 9, the outwardly spring pressed balls 69 and 70 slightly project into the detent groove formed by the enlarged orifice in the dielectric washer 78; with the balls in this position, the switch is positively retained in the "on" position until the plunger is outwardly raised; when the plunger is raised, the balls are slightly pressed towards each other as their horizontal center passes over the shank rim 65 at which time they are released to slightly project into the angular detent groove 67, and thereby the switch is positively retained in the "off" position until the plunger is outwardly depressed.

The plunger 62 containing the transverse passage 72, may be molded of the same kind of dielectric material which is used in molding the 35 dome 53, or of some other tough nonconductive plastic material.

In tooling the die for stamping the switch casing 73, provision should be made for externally impressing two inward conical indentations into the casing floor, to register with two companion impressions molded into the under side of the dielectric washer 78. These indentations should be impressed into the floor of the casing 73 from the outside and spaced so as to stabilize the washer 78 on the floor of the casing, so that the connector arm 75 cannot turn to become grounded through the casing at the sides of the rectangular opening 74.

Having described in detail the various parts comprising this signaling system, its manual operation is as follows:

On Figure 1 it will be observed that the horn button 37 is conventionally located in the center of the steering wheel hub cover 53, and in diametrically opposed vertical alignment therewith are two depressions 41 and 41' respectively containing the circuit indicator lenses 38 and 38' of the right and the left turn signaling circuits, and in diametrically opposed horizontal alignment 60 with the horn button 37 are two more depressions 39 containing the left and the right turn indicating switches 48' and 48.

Now, with Figure 1 in view, let us assume that a vehicle so equipped is parked at the curb in the usual manner, with the ignition switch turned to "off" position; in this position of the ignition switch all of the turn-lights and the stop-light are electrically inoperative, thus the entire system is electrically tamper proof while the ignition switch is locked. Now assume that the operator turns the ignition switch to "on" position preparatory to starting the engine and driving-off, in this position of the ignition switch all of the turn-lights are electrically operative and the 75

stop-light is illuminated and remains illuminated as long as the accelerator pedal of the vehicle is in the up or inoperative position. Now assuming that the operator is about to drive off, prior to backing out of an angle parking he depresses the push-button 62 of the left switch 40; this operation illuminates the red, left circuit indicator lens 35 and simultaneously causes the front and rear left turn indicating signals to "blink" and these signals continue to "blink" until the vehicle is well back into the traffic lane, at which time the switch is automatically restored to "off" position and the signals extinguished, by action of the camming means, as heretofore described. The operation, automatic action and results are the same when departing from a parallel curb parking, thus, a starting signal is comprised in this system. Now assuming that the vehicle in the traffic lane and proceeding with the flow of traffic is to be suddenly slowed down or stopped; during the course of travel and while the vehicle is in powered motion the stop signal remains "off", but the instant the foot is removed from the accelerator pedal for application to the brake preparatory to suddenly slowing down or stopping, the stop signal flashes "on", thus the action of this stop signal is instantaneous with the "beginning" of a sudden retardation or stopping maneuver and not near the end thereof, and thus is combined in the same bulb a "slow-down" signal and a "stop" signal.

Now assuming that the operator desires to indicate a contemplated left turn, he depresses the push-button 62 of the left switch 40, immediately the red left circuit indicator lens 35 is illuminated, thus assuring the operator of the operation and maintenance of that circuit, simultaneously both front and rear left side signals "blink" and thereby transmit unmistakable signals of the operator's intended left turn, to all concerned, pedestrians as well as motorists, and the "blinking" continues until the vehicle is well around the turn or completely around and again proceeding in a straight direction, depending upon the degree of turn, but regardless of the degree of turn, an extensive and adequate signal is assured with a minimum of effort or attention of the operator, because, the operator, having depressed the push-button, can then forget about it and give his undivided attention and effort to negotiating the indicated turn. Now assuming that the operator desires to indicate a right turn, the directions, operation, action and results, are similar to that for the left turn just described, however, of course, for the right turn the push-button 62 is depressed on the right switch 40, this illuminates the green indicator lens 35 and the green front and rear turn signals on the right side of the automobile.

Now assuming that the operator desires to indicate to a following motorist, an intended passing of a preceding vehicle, all traveling in the same direction, he merely depresses the push-button of the switch on the side corresponding to the side past which the passing is to be attempted; this operation sets the appropriate signal lights to "blink", and the blinking continues during the entire maneuver and until the operator again returns into his former lane of travel, at which time the depressed switch plunger is restored to "off" and the signal lights extinguished, by the automatic action of the camming means heretofore described, and thus, is provided a left and a right "passing" signal.

Now assuming that the operator desires to in-

dicate to motorists approaching his rear, an intention to reverse, he may simultaneously depress the plungers 62 of both the right and the left switches 40 and 40', this dual signal, may, by a predetermined code, signify an intention to reverse. If the reverse is part of a parallel to the curb parking maneuver, both switches will be automatically reset to "off" position and all the related signal lights automatically extinguished by the action of the camming means during the maneuver, and thus is established a "reverse" signal. However, if any driving maneuver does not entail sufficient manipulation of the steering wheel to automatically restore either or both of the switches to "off" position, the expedient of a deliberate slight swerve of the steering wheel will accomplish that result; and since the degree of swerve required need not necessarily exceed the amount usually allowed for play, the switches may be deliberately reset without appreciably affecting the direction of the front wheels.

For all audible signals, the operator presses the convenient horn-button 37.

It will be observed that this signal system comprises:

(1) A 'starting signal'	(5) A 'right turn signal'
(2) A 'slow-down signal'	(6) A 'passing signal'
(3) A 'stop signal'	(7) A 'reverse signal'
(4) A 'left turn signal'	(8) An 'audible signal'

Although I have shown and described herein a preferred embodiment of my invention, it is to be definitely understood that I do not desire to limit the application of the invention thereto, and any change or changes may be made in the materials and in the structure and arrangement of the parts, within the spirit of the invention and the scope of the subjoined claims.

What is claimed as new is:

1. The combination with a steering wheel having a hollow hub, of a stationary tube projecting into the hub and provided with a mounting member at the upper end thereof, a signal switch mounted on the mounting member overlying the hub, means for setting the switch to on position by manual operation thereof, and camming means comprising a one-way receding cam, movably confined in an arcuate slot, within the hub of said wheel, for resetting the switch to off position by action of the steering wheel in the act of steering.

2. The combination of a steering wheel having a hollow hub, a stationary tube projecting into the hub and provided with a substantially circular mounting member on the upper end thereof, a convex cover forming a closure of said hub and provided with a pair of recessed switch seats, a pair of individual switches mounted in the switch seats below the surface contour of the cover, a manually operative plunger comprising transversely contained movable contact balls in each switch, said plunger depending below the switch casing and terminating in a cam operative member, and camming means housed within the hub of said wheel for automatically actuating the cam operative members of the individual switches from on to off position by action of the steering wheel in the act of steering; said camming means comprising a relatively large diameter hub well, a shoulder in said well forming a ledge comprised of overhanging flanges, said flanges forming an annular slot which slidably confines a pair of cams, said cams being forcibly separated by an expansion spring disposed between and engaging said cams so as to yieldably urge them into raised

- 5 inclined positions upon the ramps of their companion cam-seats, said cam-seats being rigidly locked in diametrically opposed adjusted positions within said slot and thereby limiting the 5 slideable movement of said cams to an arcuate portion of said annular slot, the conjoint action of all the parts housed within the steering wheel

hub being comprised in the means whereby the manually depressed plungers of the individual switches are automatically elevated into off position by action of the steering wheel in the act of steering.

LEO J. KOBIELLA.
